UNITED STATES PATENT OFFICE.

JOHN M. FEDDERS, OF BUFFALO, NEW YORK, ASSIGNOR TO THEODORE C. FEDDERS, OF BUFFALO, NEW YORK.

RADIATOR.

988,699.

Specification of Letters Patent.

Patented Apr. 4, 1911.

Application filed January 12, 1911. Serial No. 602,204.

To all whom it may concern:

Be it known that I, JOHN M. FEDDERS, a citizen of the United States, residing at Buffalo, in the county of Erie and State of New York, have invented new and useful Improvements in Radiators, of which the following is a specification.

This invention relates to radiators of the class usually employed for cooling the water of automobile gasoline engines although the same can be used for other purposes.

The object of this invention is the production of a radiator of this character which has a core or body which presents the appearance of having individual square tubular cells or air passages but which is constructed of corrugated sheets of metal, thereby materially reducing the cost of the radiator while securing the efficiency and capacity of an individual tube radiator.

In the accompanying drawings consisting of 3 sheets: Figure 1 is a front elevation of a radiator embodying my invention. Fig. 2 is a fragmentary front elevation of the radiator, on an enlarged scale, and showing the filling between the corrugated strips omitted. Fig. 3 is a fragmentary vertical section, on an enlarged scale, in line 3—3, Fig. 4. Figs. 4 and 5 are horizontal sections in the correspondingly numbered lines in Fig. 1. Figs. 6 and 7 are vertical sections, on the same scale as Figs. 4 and 5, taken in lines 6—6 and 7—7, Fig. 2. Fig. 8 is a fragmentary perspective view of two companion corrugated strips of a tier of cells or tubes. Fig. 9 is a view similar to Fig. 8 showing a slight modification of my invention from that shown in Figs. 1—8.

Similar letters of reference indicate corresponding parts throughout the several views.

A represents the upper header or water receiving box which connects with the outlet of the engine cooling system and B the lower header or water delivery box which connects with the inlet of said system. Between said heads is arranged the cellular core or body of the radiator which embodies my invention and which is constructed as follows:—This core comprises a plurality of pairs of sheet metal strips each of which is corrugated to form a plurality of webs *c* which are arranged in line and a plurality of folded flanges *d* which project laterally from one side of said strip and each of which has its folds connected at the base

thereof with the adjacent longitudinal edges of two webs. The strips of a pair are assembled so that the crowns of the flanges of one strip engage with the central parts of the webs of the companion strip between the flanges thereof, thereby forming a tier or series of external air tubes *e* which are square in cross section and which extend lengthwise from the front to the rear side of the radiator. At opposite ends of each web the same is provided on its outer side with vertical outwardly projecting spacing beads *f* which are adapted to engage with the corresponding beads on the webs of adjacent strips, thereby holding or spacing the several rows or tiers of tubes apart and forming internal vertical water passages *g* which extend from the underside of the upper header to the upper side of the lower header. These beads *f* are preferably arranged a short distance from the ends of the webs so as to form outwardly opening vertical grooves or channels *i* between the ends of the webs of adjacent strips. The central parts of the folds of each flange preferably lie close together but the ends of these folds are separated to form an outwardly opening horizontal groove or channel *j*. A filling *k* of the same material is put in the horizontal grooves of the flanges and the vertical grooves between adjacent strips or rows of tubes, thereby producing the appearance of heavy division walls or lines between the several tubes which is so much sought after at the present time by the automobile trade.

In order to hold the webs of a coöperating pair of strips reliably in position relatively to each other, both while assembling or constructing the radiator and also while the same is in use, each of the webs is provided at its ends and preferably outside of its vertical spacing bead with an outwardly projecting or deflected locking seat or bead *l* and each flange is widened at its opposite ends so as to form laterally projecting locking lips or tongues *m* which enter the locking seats of the webs. By this means the flanges and webs are held in place relatively to each other and the square formation of the air tubes is preserved. The several strips are secured to each other and to the headers preferably by soldering in the usual manner of building radiators. If desired, the folds of the flanges may lie close to

gether throughout their length, in which case no horizontal grooves are formed at the ends of these flanges, as shown in Fig. 9. As the water passes from the upper header 5 downwardly through the vertical channels into the lower header the same is effectually cooled by the passage of the air through the horizontal tubes which present an exceptionally large cooling area.

10 I claim as my invention:

1. A radiator comprising a pair of sheet metal strips each of which is corrugated to form a plurality of webs and laterally projecting doubled flanges at the opposing 15 edges of said webs, the flanges of each strip engaging with the webs of the other strip between the flanges of the latter so as to form a plurality of tubes, the ends of the folds of each flange being separated to form 20 grooves between the same and a filling arranged in said grooves.

2. A radiator comprising a plurality of pairs of sheet metal strips each of which is corrugated to form a plurality of webs 25 which are arranged in line and laterally projecting doubled flanges at the opposing edges of the webs, the flanges of each strip of a pair engaging with the webs of the companion strip of the pair between the 30 flanges of the latter, the webs of each strip

being provided at their ends with outwardly projecting spacing beads which engage with the corresponding beads of the webs of an adjacent strip forming a groove between the same and a filling arranged in said 35 groove.

3. A radiator comprising a plurality of pairs of sheet metal strips each of which is corrugated to form a plurality of webs which are arranged in line and laterally 40 projecting doubled flanges at the opposing edges of the webs, the flanges of each strip of a pair engaging with the webs of the companion strip of the pair between the flanges of the latter, the webs of each strip 45 being provided at their ends with outwardly projecting spacing beads which engage with the corresponding beads of the webs of an adjacent strip forming a groove between the same and the ends of the folds of each 50 flange being separated to form a groove between the same and a filling arranged in said grooves.

Witness my hand this 11th day of January, 1911.

JOHN M. FEEDERS.
